UNITED STATES PATENT OFFICE

132,127

DESIGN FOR A SERVICE PLAQUE

Raymond Paul Jones, Dillon, Mont.

Application September 12, 1941, Serial No. 103,319

Term of patent 3½ years

To all whom it may concern:

Be it known that Raymond Paul Jones, a citizen of the United States of America, residing at Dillon, in the county of Beaverhead and State of Montana, has invented a new, original, and ornamental Design for a Service Plaque, of which the following is a specification, reference being had to the accompanying drawing, forming part thereof.

I claim:

The ornamental design for a service plaque, as shown.

RAYMOND PAUL JONES.
